UNITED STATES PATENT OFFICE

LEON L. ALLYN, OF KALAMAZOO, MICHIGAN, AND WILLIAM A. POOL, OF RIDGEFIELD PARK, NEW JERSEY, ASSIGNORS TO MASTER-CRAFT CORPORATION, OF KALAMAZOO, MICHIGAN

TEMPORARY BINDER

Application filed November 11, 1929. Serial No. 406,228.

The main object of this invention is to provide in a temporary binder or loose sheet holder an improved adjusting means whereby the binder may be rapidly adjusted to tension or tighten the same and quickly released for opening.

Objects relating to details and economies of our invention will appear from the description to follow. The invention is defined and 10 pointed out in the claims.

A structure which is a preferred embodiment of our invention is illustrated in the accompanying drawings, in which:

Fig. 1 is a perspective view of our improved temporary binder, the adjusting mechanism being shown by dotted lines within one of the covers.

Fig. 2 is a plan view with the rear wall of the cover containing the adjusting mechanism removed.

Fig. 3 is an enlarged fragmentary view of parts shown in Fig. 2.

Fig. 4 is a fragmentary view, parts being sectioned on line 4—4 of Figs. 2 and 5.

Fig. 5 is a fragmentary view on line 5—5 of Figs. 2, 3 and 4, the finger piece being shown in one position by full lines and in another position by dotted lines.

Referring to the drawings, 1 represents a body of sheets. The clamping bars 2 are pivotally mounted on the inner edges of the covers 3 and 4, the hinges being shown at 5.

Binding strips 6 are connected to the cover 3 and adjustably connected to the cover 4 which is chambered to receive the adjusting mechanism, the inner wall 7 of this cover having a longitudinal slot 8 therein.

Within the cover chamber, we mount a rack bar 9, the slot being disposed at one side of this bar 9.

The crosshead or adjusting member 10 is slidably mounted on the rack bar 9, the binding strips being secured to this crosshead.

A pawl 11 is mounted on the pivot 12 carried by the adjusting member 10 to coact with the rack bar, the spring 13 acting to urge the pawl into engagement with the rack bar.

To release the pawl and hold it in its released position, we provide a rotatably mount-

ed cam-releasing member 14, this member being rotatably mounted in the adjusting member to engage the tail 15 on the pawl, the releasing member having a flattened side 16 which permits the pawl to engage the ratchet bar, the pawl being disengaged and held in disengaged position as indicated by dotted lines in Fig. 3 by the rotative movement of this releasing member.

The releasing member is hollow, providing a chamber 17 in which the finger piece 18 is mounted, the finger piece being supported by the pivot 19. This finger piece projects through the slot 8 and is of a general T-shape providing a head 20 for convenience in grasping.

The finger piece has a flattened face 21 projecting below the releasing member and engaged by the blade spring 22 mounted at 23 and acting to normally hold the finger piece in its collapsed position. However, the finger piece may be readily grasped and swung upright, turned to the position shown by dotted lines in Fig. 5 to disengage and hold the pawl in its disengaged position or merely swung to an upright position for grasping to tension the binder or to draw the adjusting member toward the outer end of the cover which applies stress to the binding strips.

Binders embodying our improvements are simple and economical in structure and may be rapidly manipulated to close or release the binder.

Having thus described our invention, what we claim as new and desire to secure by Letters Patent, is:

1. A temporary binder comprising covers and binding strips, one cover being chambered and having a longitudinal slot in its inner wall, a ratchet bar arranged within said chamber, an adjusting member to which said binding strips are connected slidably mounted on said ratchet bar, a spring-actuated pawl on said adjusting member coacting with said ratchet bar, a chambered pawl-releasing cam rotatably mounted on said adjusting member in coacting relation to said pawl, a finger piece pivotally mounted within said pawl-releasing cam to project through said slot in said cover whereby the pawl may

be released and the adjusting member shifted on said ratchet bar through said finger piece, said finger piece having a flattened face projecting below said cam, and a blade spring mounted on the underside of said adjusting member to coact with said flattened face of said finger piece and acting to hold the finger piece in collapsed position.

5 2. A temporary binder comprising covers and binding strips, one cover being chambered and having a longitudinal slot in its inner wall, a ratchet bar arranged within said chamber, an adjusting member to which said binding strips are connected slidably mounted on said ratchet bar, a spring-actuated pawl on said adjusting member coacting with said ratchet bar, a chambered pawl-releasing cam rotatably mounted on said adjusting member in coacting relation to said 10 pawl, and a finger piece pivotally mounted within said pawl releasing cam to project through said slot in said cover whereby the pawl may be released and the adjusting member shifted on said ratchet bar through said 15 finger piece.

20 3. A temporary binder comprising covers and binding strips, one cover being chambered and having a longitudinal slot in its inner wall, a ratchet bar arranged within said chamber, an adjusting member to which said binding strips are connected slidably mounted on said ratchet bar, a spring-actuated pawl on said adjusting member coacting with said ratchet bar, a chambered pawl-releasing cam rotatably mounted on said 25 adjusting member in coacting relation to said pawl, and a finger piece on said pawl-releasing cam projecting through said slot in said cover whereby the pawl may be released and 30 the adjusting member shifted on said ratchet bar.

35 4. A temporary binder comprising covers and connecting binding strips, of a ratchet bar carried by one of the covers, an adjusting member for said binding strips slidably mounted on said ratchet bar, a spring-actuated pawl on said adjusting member coacting with said ratchet bar, and a pawl-releasing member rotatably mounted on said adjusting 40 member and provided with a collapsible finger piece whereby said releasing member may be adjusted for engaging or holding the pawl in released position and said adjusting member may be manipulated.

45 5. A temporary binder comprising covers and connecting binding strips, of a ratchet bar carried by one of the covers, an adjusting member for said binding strips slidably mounted on said ratchet bar, a spring-actuated pawl on said adjusting member coacting with said ratchet bar, and a pawl-releasing member mounted on said adjusting member and provided with a finger piece whereby 50 said releasing member may be adjusted for

engaging or holding the pawl in released position and said adjusting member may be manipulated.

6. In a temporary binder, the combination of covers, an adjusting mechanism comprising a ratchet bar carried by one of the covers, an adjusting member mounted on said ratchet bar, a pawl on said adjusting member coacting with said ratchet bar, and a releasing member for said pawl provided with a collapsible finger piece adapted for the manipulation of the releasing member and said adjusting member.

7. In a temporary binder, the combination of covers, an adjusting mechanism comprising a ratchet bar carried by one of the covers, an adjusting member mounted on said ratchet bar, a pawl on said adjusting member coacting with said ratchet bar, and a releasing member for said pawl provided with a finger piece adapted for the manipulation of the releasing member and said adjusting member.

In witness whereof we have hereunto set our hands.

LEON L. ALLYN.
WILLIAM A. POOL.
